TOY WHISTLE

Leslie H. Berk, Rocky River, Ohio

Application November 13, 1948, Serial No. 149,610

Term of patent 14 years

(Cl. D34—15)

To all whom it may concern:

Be it known that I, Leslie H. Berk, a citizen of the United States, residing at Rocky River, in the county of Cuyahoga and State of Ohio, have invented a new, original, and ornamental Design for a Toy Whistle, of which the following is a specification, reference being had to the accompanying drawings, forming a part thereof.

I claim:

The ornamental design for a toy whistle, substantially as shown.

LESLIE H. BERK.
